UNITED STATES PATENT OFFICE.

ELLSWORTH TILDEN, OF COLUMBIA FALLS, MONTANA.

DEVICE FOR MARKING LAYING HENS.

1,280,588.

Specification of Letters Patent.

Patented Oct. 1, 1918.

Application filed February 27, 1918. Serial No. 219,546.

To all whom it may concern:

Be it known that I, ELLSWORTH TILDEN, a citizen of the United States, residing at Columbia Falls, in the county of Flathead and 5 State of Montana, have invented certain new and useful Improvements in Devices for Marking Laying Hens; and I do hereby declare the following to be a full, clear, and exact description of the invention, such as 10 will enable others skilled in the art to which it appertains to make and use the same, reference being had to the accompanying drawings, and to the letters and figures of reference marked thereon, which form a 15 part of this specification.

This invention relates to new and useful improvements in attachments to hen nests for marking the hen as it enters the nest, and consists of a simple and efficient device 20 of this nature having various details of construction, combinations and arrangements of parts which will be hereinafter fully described, shown in the accompanying drawings and then specifically defined in the appended 25 claims.

My invention is illustrated in the accompanying drawings which, with the letters of reference marked thereon, form a part of this specification and in which:

30 Figure 1 is a vertical sectional view through the nest, and

Fig. 2 is a horizontal plan view.

Reference now being had to the details of the drawings by letter:

35 A designates a nest box which is of any desirable shape and is provided with a hinged door B adapted to swing in both directions. A tilting platform C is mounted within the box upon which the nest C' is located. A coiled spring D is fastened at one end to said platform and its other end D' is fastened to the end of the box. Said platform has a projection E' upon its under surface and which is convexed and rests 40 upon the bottom of the box, and which is longitudinally apertured for the reception of the rod E which is journaled in the opposite walls of the box. A stop F is mounted upon the free end of the platform near 45 the door and is adapted when the platform is tilted to prevent the door being opened while the hen is upon the nest.

A rotatable disk H is mounted upon a shaft H' which is driven by clock mechanism mounted in the compartment I, and so arranged that the disk will make a single

rotation within five minutes or so. A vertically movable bar J is mounted in the partition A' of the box and is in the path of the door B adapted to be actuated by the same as the door swings open, causing the latch J' to be raised out of the notch H² permitting the same to rotate. A swinging member O has a branching arm O' which is hinged at O² upon the top of the box, and one end of the member O is in the path of a pin K projecting from the face of the disk adapted to tilt the member O at each revolution of said disk.

A vial or bottle R is fastened to one end of the member O and is adapted to contain a coloring solution. A pin T projects from the top of the box and when the member O is tilted to the position shown in dotted lines, the vial is raised so that the pin will enter the solution in the vial, and when the disk rotates to release the member O, the latter will return to its normal position by gravity and the solution upon the end of the pin is adapted to drop on to the hen 80 upon the nest and thus mark the same.

It will be understood that the device is designed for use in connection with hens having plumage of a light color, which are the best types of laying fowl, and which will 85 serve to identify the laying of an egg as the hen enters the nest.

In operation, after the hen enters the box the door will actuate the catch to release the disk permitting the same to make a revolution and after the hen passes by the door the latter will return to its closed position and as the hen walks upon the nest the platform will tilt and lock the door. When the disk makes one revolution the member 90 O will swing upon its hinge, the pin T will enter the bottle and after the pin K passes by the end of the member O the latter will tilt down and permit the pin T to drip the marking solution upon the back of the hen. 95 100

What I claim to be new is:

1. A device for marking hens consisting of a box with a hinged door, a tilting platform, a nest thereon, a rotatable disk and clock work mechanism for operating the same, a latch engaging the disk and releasing the disk as the door is opened, a tilting gravity member actuated by each revolution of the disk, a bottle upon one end of said member adapted to contain a marking 105 solution, a projection upon the box adapted to enter the bottle as the platform is tilted. 110

2. A device for marking hens consisting of a box with a hinged door, a tilting platform, a nest thereon, a rotatable disk and clock work mechanism for operating the same, a latch engaging the disk and releasing the disk as the door is opened, a tilting gravity member actuated by each revolution of the disk, a bottle upon one end of said member adapted to contain a marking solution, a projection upon the box adapted to enter the bottle as the platform is tilted, the platform designed to lock the door as the hen enters the nest.
3. A device for marking hens consisting of a box with a hinged door, a rotatable disk and clock work mechanism for operating the same, a latch engaging the disk and releasing the disk as the door is opened, a tilting gravity member actuated by each revolution of the disk, a bottle upon one end of said member adapted to contain a marking solution, a projection upon the box adapted to enter the bottle as the platform is tilted, a tilting spring pressed platform,

a nest upon the platform and a stop upon the platform adjacent to said door.

4. A device for marking hens consisting of a box, a hinged door forming a part of the box, a tilting platform, a nest thereon, a rotatable notched disk and means for operating the same, a pin projecting from the disk, a movable bar in the path of the door, a catch engaging said notch and actuated by said bar as the door is opened, a tilting member mounted within the box in the path of said pin, a bottle upon said member adapted to contain a marking solution, a projection upon the box adapted to enter said bottle as the member is tilted, and means upon said platform for locking the door as the hen enters the nest.

In testimony whereof I hereunto affix my signature in presence of two witnesses.

ELLSWORTH TILDEN.
